UNITED STATES PATENT OFFICE.

ANNZZANETTA BERTHA JONES, OF DETROIT, MICHIGAN.

DESIGN FOR A PENCIL-HOLDER.

55,565.

Specification for Design.

Patented June 29, 1920.

Application filed December 13, 1917. Serial No. 207,017. Term of patent 14 years.

To all whom it may concern:

Be it known that I, ANNZZANETTA BERTHA JONES, a citizen of the United States, residing at Detroit, county of Wayne, and State of Michigan, have invented a new, original, and ornamental Design for a Pencil-Holder, of which the following is a specification.

The drawing is a perspective view of a pencil holder embodying my new design.

I claim:

The new, original, and ornamental design for a pencil holder substantially as shown.

ANNZZANETTA BERTHA JONES.
